CARBURETOR

Milton E. Chandler, New Britain, Conn., assignor
to Chandler-Evans Corporation, a corporation
of Delaware

Application August 14, 1941, Serial No. 406,776

12 Claims. (Cl. 261—69)

My invention relates to carburetors.

It has among its objects to provide improved air flow controlling mechanism for carburetors, and, more particularly, such an improved mechanism adapted to use in connection with an airplane carburetor. A further object of my invention is to provide such improved air flow controlling mechanism of a type adapted to minimize turbulence and wherein the air flow is so distributed in its passage to the engine as to make possible an improved and uniform distribution of the fuel to the several cylinders, while also producing an average metering force distributed over an air passage of substantial area, as distinguished from obtaining a metering force produced at one or two selected points in the air passage as is usual in prior constructions. Further objects of my invention are to provide an improved rectangular air meter including connections for measuring air flow therethrough, and to provide an improved cooperating throttle structure controlling the air flow therethrough to the engine. A still further object of my invention is to provide such improved air flow controlling means including such improved throttle means cooperating with the air meter and the fuel nozzle or inlet means, whereby it is made possible to effect a more accurate control of the fuel flow controlling means provided in the carburetor. Other objects of my invention include the provision of an improved air metering and throttling structure whereby while obtaining the above results, it is also made possible to produce an air meter of the desired large cross section while at the same time producing a structure which is light and which also permits ready assembly, or disassembly for inspection and repair, while also being adapted to carry the associated control mechanisms of the carburetor in convenient locations relative to the air meter. These and other objects and advantages of my improvements will, however, hereinafter more fully appear.

In the accompanying drawings, I have shown for purposes of illustration one embodiment which my invention may assume in practice.

In these drawings,

Figure 1 is a top plan view of the scoop portion of my improved air flow controlling mechanism applied to an airplane carburetor;

Fig. 2 is a bottom plan view of the same as seen from the manifold portion thereof;

Fig. 3 is an enlarged transverse section on line 3—3 of Figure 1 with parts broken away to facilitate illustration of one of the throttle bars;

Fig. 4 is a like enlarged detail section showing the throttle bars of Figure 3 in a different position;

Fig. 5 is an enlarged section on line 5—5 of Figure 1;

Fig. 6 is a like section on line 6—6 of Figure 1;

Fig. 7 is a like section on line 7—7 of Figure 1;

Fig. 8 is a like section on line 8—8 of Figure 1;

Fig. 9 is a perspective view of certain of the 10 Venturi bars and one of their associated connecting end plates disposed in spaced relation to facilitate illustration;

Fig. 10 is a similar view of the same with the opposite connecting end plate;

Fig. 11 is an enlarged assembled view of one of the Venturi bars and its associated end plates, a portion of the bar being broken away and the bar and plates being shown in section to facilitate illustration;

Fig. 12 is a diagrammatic plan view of the 20 assembled Venturi bar and plate unit showing a preferred arrangement of the suction holes in the bars, and

Fig. 13 is a detail perspective of the compensating valve.

In this illustrative construction, I have shown the same as comprising a generally rectangular casing, indicated at 1, and having an improved 30 rectangular scoop passage 2 therein leading to improved Venturi mechanism including spaced Venturi bars 3 providing a plurality of improved elongated parallel throat passages 4 and delivering into a rectangular manifold passage 5, wherein improved elongated parallel throttles 6 are disposed between a fuel inlet nozzle or bar 7 and the Venturi throats 4 and cooperate in an improved manner with one another, the manifold passage 5, the improved Venturi mechanism, and the throttle bar 6. The main casing 1 also carries improved fuel flow controlling mechanism, generally indicated at 8, and responsive to changes in the air flow through the scoop passage 2 to control the fuel flow through a pipe 9, and thereby control the operation of a fuel pressure

40 regulator 10 in the general manner described and claimed in my copending application, Serial No. 474,736, filed February 4, 1943, which is a continuation of application Serial No. 361,239, filed October 15, 1940.

45 Referring more particularly to the Venturi mechanism, it will be noted that the Venturi bars 3, as illustrated, are straight and four in number and of an improved construction and connected at their opposite ends between improved end plates 11 and 12 in an improved manner to form

an improved Venturi bar assembly unit. These end plates 11 and 12 are herein generally rectangular in shape and received in corresponding openings 13 and 14 in opposite ends of the main casing 1. Each bar 3 is of streamlined section and has a hollow longitudinal chamber 15 therein and the plates 11 and 12 are provided with projecting holding portions or extensions 16 adapted to be received in the opposite ends of these chambers 15. Each of the end plates 11 and 12 is also provided with a recess portion 17 having a corresponding sealing gasket 17a therein and surrounding each of the extensions 16 and adapted to receive the extremity of the bar 3; dowel pins 18 in the recesses 17 also connecting each bar to the end plates 11 and 12 above and below the bar, in such manner as to produce a rigid unitary construction. As shown, the outer faces of the two outer longitudinal bars 3 engage longitudinally disposed sealing strips 19, shown as tubular and formed of soft rubber and seated in grooves in the side walls of the scoop passage 2, while the end plates 11 and 12 also carry rectangular peripheral gaskets 20, in this case also of rubber, engaged by outer casing end plates 21 and 22 to clamp the rectangular Venturi assembly securely in position with its ends in the openings 13 and 14 in the casing 1. A plurality of spaced dowels 23 is also provided at each end of the Venturi assembly and carried by the casing end plates 21 and 22 and extended through suitable apertures 24 in the end plates 11 and 12, in such manner as to insure correct location. As illustrated, a narrow transverse rib or bridge 25 extends across the bottom of the throats 4 midway between the ends of the Venturi bars 3 and the inner edge of each bar 3 extends into a suitable clearance notch or recess 26 in this rib 25. Further, the two outer Venturi bars 3 are also connected to the mouth of the scoop passage 2 by plate shields 27, herein suitably connected to the flaring mouth of the scoop passage 2 at their outer ends, as by bolts 28, and having their inner ends received in suitable longitudinal grooves 29 in the adjacent edges of the outer Venturi bars. These shields 27 thus act to form two outwardly flaring sides of the scoop passage 2 to direct the air into three inner Venturi passages 4. As shown, also, a series of static scoop tubes 30, herein spaced equally longitudinally along the shields 27, project through each of these shields angularly and these tubes at their inner ends communicate with longitudinal passages 31 leading to fuel flow control devices as hereinafter described.

The air flowing through scoop passage 2 thus passes through three parallel Venturi passages 4 which extend the full width of the inner bore of the casing between the plates 11 and 12. Here, it will, however, be noted that while various suction aperture arrangements may be provided in the Venturi bars, in the preferred arrangement thereof illustrated, the two outer bars 3 are free from such apertures, while the two inner bars are provided with the arrangement of apertures shown in Figure 12. Each of the inner bars is provided with a series of equally spaced lateral apertures or suction holes 32 on its outer face, and an additional smaller series of apertures 33 on its inner face adjacent each end of the bar. This arrangement is preferred, as it is found to give satisfactory suction effects in various throttle positions. The chambers 15 in these two inner bars 3 also communicate, through apertures 34 in the extensions or centering bosses 16 with the chamber 35 formed by the gasket 20 between the

plate 12 and the end plate 21, with a passage 36 leading from this chamber 35 to the control devices responsive to the Venturi suction and as hereinafter described.

Cooperating with my improved rectangular Venturi mechanism is also improved throttle mechanism controlling the flow from the Venturi passages 4 to the engine manifold passage 5, and past the fuel inlet nozzle or bar 7. Herein, two throttle bars 6 are disposed transversely of the manifold passage 5 parallel to the Venturi bars 3, these throttle bars being journaled for rotation on their longitudinal axes in the transverse rib or bridge 25 and at the opposite sides of the passage 5. These bars cooperate with one another and with the side and end walls of the rectangular manifold passage 5, in such manner as completely to close the latter passage in the closed position of the throttle 6, while, in their open positions, cooperating with the Venturi bars 3 in further controlling and distributing the flow of air into the manifold 5 and past the inlet nozzle or bar 7

As shown, each of these bars 6 is of like construction and hollow and of generally elliptical cross section, with a shaft 37 extending longitudinally thereof and having reduced ends 38 journaled in the end plates 21 and 22. Herein each throttle member 6 comprises two longitudinally spaced hollow members 39 suitably fixed to the shaft 37 as by rivets 40. Between these members 39 I herein also show a sleeve 41 surrounding the shaft 37 and in turn surrounded by split bearing members 42 held in position by a snap ring 43; these split members 42 being disposed in an aperture 44 extending through the bar 25 and being positioned in this aperture in such manner as thereby to provide a bearing for each throttle 6 midway between the ends thereof. Herein also it will be noted that these throttles 6 are sealed along the side walls of the manifold chamber 5 when in their fully closed position or approaching this position, the adjacent edge 45 of each throttle then being received in an arcuate sealing or masking portion 46 provided on the adjacent wall of the chamber. Moreover, the opposite ends of each throttle 6 also have a sealed connection to the end walls of the passage 5. Each of the same herein has an end disc 47 abutting the end of each member 39 and each end disc projects beyond the member 39 within an annular cooperating sealing member 48 carried in a suitable recess 49 in the main casting 1.

No claim, however, is herein made to the particular construction of the throttle members illustrated or the means for journaling the same or for effecting sealing at the ends of these throttle members, this being the invention of Paul P. Bauernschmid and described and claimed in a copending application Serial No. 406,789, filed August 14, 1941.

Thus, with an operating lever 50 suitably connected to one of the throttle shafts 37 and the two shafts connected by toothed sectors 51, it will be evident that the same may be moved in unison into a completely closed position in which they completely prevent flow through the passage 5, due to their sealed connections along the side walls and their sealed connection to the end walls of the passage 5. Further, when the same are opened and move in the direction of the arrows indicated in Figure 4, it will be evident that their sealed end connections will always be maintained, while in the initial stages of this opening movement their side sealed connections will also be maintained, and that accordingly any air passing

through the Venturi passages 4 will first pass between the adjacent longitudinal edges of these throttle means 6, i. e. directly in line with the fuel bar 7. As a result, the entering air is thoroughly mixed with the fuel passing through the diverging fuel bar outlets 7a into this stream of incoming air and throughout the whole length of the bar 7, which in turn extends throughout the full width of the manifold passage 5. When the throttles are further opened, it will also be evident that after increasing the space between their adjacent edges, and therefore the flow to the fuel bar 7 throughout the full length of the latter, they will also permit air to flow between the throttles 6 and the side walls of the manifold passage 5, and in their fully open position (illustrated at the right in Figure 3) will be disposed opposite the two outer Venturi passages 4 while the fuel bar 7 is opposite the middle Venturi passage, all in such manner as to effect a uniform mixing of the air and fuel while affording a minimum obstruction to the air flow.

In my improved construction, the end plate 21 carries an improved arrangement of operating diaphragms and controlling mechanism controlling the fuel flow through the pipe 9 in such manner as to control the fuel pressure supplied to the carburetor, as described and claimed in my copending application mentioned above.

In this improved arrangement a diaphragm 52 is clamped between an inclined face 53 and a small cover member 54, both being carried by a casing cover member 55 clamped to the end plate 21. One side of this diaphragm 52 is connected through a passage 56 with the longitudinal passage 31 (supplied from the static scoop tubes 30 as hereinafter described), while the opposite side of this diaphragm is connected through a restricted opening 57 (Fig. 6) with the passage 36 communicating through chamber 35 and passages 34 with the chambers 15 inside the Venturi bars 3. As shown in Figure 6, a more restricted opening 58 is also provided leading from the passage 36 to the opposite side of the diaphragm 52. Moreover, this diaphragm is normally biased by a spring 59, the tension of which is adjusted by a threaded connection 59a, in such manner as to cause a button 60 on the opposite side of the diaphragm 52 to press against a smaller cooperating diaphragm 61 and thereby close a port 62 controlling the connection between the pipe 9 leading from the regulator 10 and a passage 63 delivering into the manifold chamber 5, all in such manner as thereby to control the pressure acting on the regulator 10 and thereby control the pressure in the regulator to vary the fuel pressure in accordance with variations in the air flow through the air meter, all as described and claimed in my copending application mentioned.

The end plate 21 and cover 55 carry an improved arrangement of aneroid mechanism operating to vary the controlling pressure and the fuel pressure in accordance with changes in altitude and temperature of the air stream. As illustrated, this mechanism includes a sealed Sylphon-type bellows 64 having a tube 65 extending into the air stream through the middle Venturi passage 4 and responsive to changes in temperature in the air stream, while the bellows 64 is responsive to changes in pressure due to changes in altitude and is disposed in a chamber 66 which communicates with the longitudinal passages 31 and the static tubes 30. Thus, this bellows 64 upon any changes in scoop pressure, and/or changes in temperature of the tube 65,

causes a valve 67, normally maintained in open position by a coiled spring 67a, to control the flow from chamber 66 through radial ports 68 into an axial passage 69 in a normally stationary sleeve 70 and the resultant flow from this axial passage 69 through a lateral port 69a to communicating annular passage means 71 and the passage 56 leading to the scoop connecting side of the diaphragm 52. Here attention is also directed to the fact that the sleeve 70 is herein provided with a threaded extension 72 and threaded into a packing gland 73 having the annular passage 71 therein, while adjusting nuts 74 are provided on the outer end of this threaded extension 72. Thus it will be apparent that by reason of the spacing of the diaphragm 52 in its non-coaxial relation with the valve 67, it is made possible for the ported member 70 to be adjusted longitudinally to vary the relation of the ports 68 with respect to the valve 67 with facility whenever desired.

Attention is here also directed to the fact that the cross bar or rib 25 makes it possible for an accelerating pump to be conveniently carried therein at a central point in the air stream passing through the air meter. As shown, an accelerating pump plunger 75 is movable longitudinally in a sleeve 76 extending longitudinally of the rib 25 at a point between the throttle 6 and the Venturi bars 3 and movable transversely of both of the latter. Herein, this plunger has a diaphragm 77 connected to the outer end thereof and disposed in a chamber 78 in a cap 78a, while a coiled spring 79 normally biases the plunger to seat upon and close a port 80 connected to communicating passages 81, 82, 83 which, in turn, communicate with a chamber 84 receiving fuel from the pressure side of the regulator 10 through a passage 85, while ports 86, when the plunger 75 is open, deliver fuel from the port 80 into the manifold passage 5 on opposite sides of the rib 25. Further, it will be observed that manifold pressure is supplied through a passage 87 to one side of the diaphragm 77 and is also supplied through a restricted passage 88 to the other, or spring pressed, side of that diaphragm. Thus, when the throttles 6 are opened quickly, it will be apparent that the rise in pressure in the manifold 5 will be communicated through the passage 87 to the adjacent side of the diaphragm 77 in such manner as to cause the plunger 75 to move to the left (Fig. 3) and immediately open port 80 to increase the fuel supply momentarily. When, however, sufficient time has elapsed, the flow through the restricted opening 88 will be sufficient to reestablish a balanced pressure on opposite sides of the diaphragm 77 and thereby again close the port 80. Should, however, the throttles 6 be opened slowly, this port 80 will ordinarily not be opened.

It will also be noted that this improved construction permits an improved compensating valve mechanism to be carried on the end plate 22. This mechanism includes a diaphragm 89 having one side thereof connected through a bleed 90 and passage 91 to the static scoop tubes 30, while the other side of this diaphragm is connected to the fuel supply from the regulator 10 through a connection 92. Herein, this diaphragm carries a compensating valve 93 having spaced seats 94 and 95 on a valve seat member 96 at opposite ends of the valve, while the valve 93 is provided with an axial passage 97 communicating through radial ports 97a with the

fuel connection 92 and through a port 98 and an annular passage 99 which, in turn, communicate through a slot 99a and chamber 99b with a passage 100 leading to one end of the fuel bar 7. In this construction, the diaphragm 99 is as usual biased to a position closing the valve 93, by a spring 101 acting against an abutment 102 adjustable by a threaded pin 103. Attention is also directed to the fact that the valve 93 is provided with triangular guiding portions 104 at its opposite ends and with external annular passages 105 for also permitting an external flow around and along the valve.

It will be noted that the cross bar or rib 25 is of considerable depth, providing a septum extending transversely of the main air passage provided within the carburetor body, the same being a relatively narrow member and having those edges which in Fig. 3 are uppermost and lowermost, respectively, curved, as shown in Figs. 1 and 2, for stream-lining. At its upper part (Fig. 3) this septum has the clearance notches in which considerable portions of the bodies of the Venturi bars are received, and in the body of the septum below these notches is the chamber in which the accelerating pump is received, said pump being arranged to supply fuel to the outlet ports 86 a short distance below the pump, which ports slant downwardly (Fig. 3) to the proximate lateral faces of the septum, these ports being in line with the elongated passage between the two inner Venturi bars, and these ports being above (Fig. 3) and in line with and a short distance from the line where the throttle bars in their closed position meet each other. The middle bearings for the throttle bars are also provided within this septum, and furthermore, the fuel bar 7 extends through it at a point somewhat above (Fig. 3) the lower margin of the septum. The septum, furthermore, as shown in Fig. 3, serves to provide within it a portion of the passage 87 previously referred to, which is intended to be subject to manifold pressures.

The rubber sealing strips 19, which abut against the sides of the outermost Venturi bars, serve to an extent to support the bars in a cushioned manner and to reduce vibration and permit expansion and contraction under temperature changes. The rubber gaskets 20 also support the Venturi bars in a cushioned manner and reduce vibration and obviate close tolerances, this being in addition to their function of providing effective seals at the ends of the bars against leakage of fluid. The plates 21 and 22 clamp the plates 11 and 12 against the ends of the Venturi bars in a resilient manner. The plates 11 and 12 serve to tie the Venturi bars together in a definite spaced relation, the plates and bars being provided with means whereby they interengage or interlock, for which purpose one element has preferably a locating boss or projection fitting a corresponding recess in the other.

As a result of my improved construction including the Venturi bars, it is made possible to obtain a new and uniform distribution of the air flow, the bars acting to produce three Venturi passages extending throughout the whole length of the bars. Further, as a result of this construction and the new throttle bars cooperating therewith and extending longitudinally of the Venturi bars and having both these throttle bars and the Venturi bars sealed at their sides and ends, it is made possible further to assist in obtaining an improved mixture while controlling

the pressure thereof supplied to the engine cylinders and while also markedly increasing the metering force for actuation of the various control devices. Attention is further directed to the fact that, due to the provision of the improved sealed Venturi unit and sealed throttle bars, it is made possible to eliminate air leaks past either the Venturi bars or the throttle bars, the Venturi bars being sealed at all times, and the throttle bars being sealed at their ends at all times and along their sides in their fully closed position or positions approaching and leaving the same, while at the same time, under these conditions of small air flow, directing the air in such manner as to form an effective mixture with the fuel emerging from the apertures in the fuel inlet bar. Attention is also directed to the improved Venturi unit structure provided, and to the facility with which the same may be produced and assembled or removed in the carburetor, with this unit longitudinally insertable or withdrawable through the end apertures in the main casing. These and other advantages of my improvements will, however, be apparent to those skilled in the art.

While I have herein specifically described one embodiment which my invention may assume in practice, it will be understood that this form of the same is shown for purposes of illustration, and that the construction may be modified and embodied in various other forms without departing from its spirit or the scope of the appended claims.

What I claim as new and desire to secure by Letters Patent is:

1. A carburetor comprising a body or casing having a through opening or passage of generally rectangular cross section extending from a face having an enlarged inlet or scoop to an opposite face at which a manifold connection is made, the carburetor being provided within said passage with bars providing a plurality of narrow substantially rectangular Venturi passages and being provided beyond the discharge of the Venturi passages with a pair of throttle bars adapted to be turned to a closed position and to various open positions and adapted when in an open position to provide between them a restricted passage, and the carburetor also having in its main passage in a region close to and somewhat beyond said restricted passage in the direction of air flow a fuel bar extending lengthwise of said restricted passage, shield plates arranged to provide a flaring scoop portion adjacent the entrance of the main passage having inner edges in proximity to the air-receiving ends of the marginal Venturi bars and having outer edge portions attached to the body wall, and a relatively deep septum crossing the main passage transversely of the Venturi bars adjacent the discharge sides of said bars, said septum having clearance notches receiving substantial portions of the respective Venturi bars, said septum carrying intermediate bearings for said throttle bars and providing an intermediate support for said fuel bar, and said septum further providing within it in a location forwardly of the throttle bars a chamber and an auxiliary fuel pump within the chamber, said pump having a discharge intermediate the ends of the septum, and the septum having auxiliary fuel discharge ports at its side faces in locations forwardly of the throttle bar axes and between said axes.

2. A carburetor comprising a body or casing

having a through opening or passage of generally rectangular cross section extending from a face having an enlarged inlet or scoop to an opposite face, the carburetor being provided within said passage with means providing a plurality of narrow substantially rectangular Venturi passages and being provided beyond the discharge of the Venturi passages with a pair of throttle bars adapted to be turned to a closed position and to various open positions and adapted when in an open position to provide between them a restricted passage, and the carburetor also having in its main passage in a region close to and somewhat beyond said restricted passage in the direction of air flow a fuel bar directed longitudinally of said restricted passage, said Venturi bars being formed as separate individual members, plates extending across said members at the respective ends of the latter for tying them together set in apertures formed in the carburetor body at opposite sides of the body, separate plates attached to the body exteriorly and cooperating with said first-named plates in holding the Venturi bars firmly in position in a detachable manner, sealing strips interposed between the side faces of the marginal Venturi bars and the adjacent walls of the body, and shield plates arranged to provide a flaring scoop portion adjacent the entrance of the main passage having inner edges in proximity to the air-receiving ends of the marginal Venturi bars and having outer edge portions attached to the body walls.

3. A carburetor comprising a body or casing having a through opening or passage of generally rectangular cross section extending from a face having an enlarged inlet or scoop to an opposite face, the carburetor being provided within said passage adjacent the base of the scoop with a plurality of straight bars in the same plane, said bars being four in number and providing a middle or median Venturi passage and side Venturi passages, the carburetor being provided beyond the discharge of the Venturi passages with a pair of throttle bars turning on axes substantially in line with the respective side Venturi passages and adapted to be moved to a closed position and to various open positions and adapted on first opening to provide a restricted passage at the median portion only of the main passage and on full opening to provide outer passages as well as a median passage, and the carburetor also having in its main passage in a region close to and somewhat beyond said median restricted passage in the direction of air flow, a fuel bar directed longitudinally of said passage.

4. A carburetor comprising a body or casing having a through opening or passage of generally rectangular cross section extending from a face having an enlarged inlet or scoop to an opposite face, the carburetor being provided within said passage adjacent the base of the scoop with a plurality of straight bars in the same plane, said bars being four in number and providing a middle or median Venturi passage and side Venturi passages, the carburetor being provided beyond the discharge of the Venturi passages with a pair of throttle bars turning on axes substantially in line with the respective side Venturi passages and adapted to be moved to a closed position and to various open positions and adapted on first opening to provide a restricted passage at the median portion only of the main passage and on full opening to provide outer pas-

sages as well as a median passage, and the carburetor also having in its main passage in a region close to and somewhat beyond said median restricted passage in the direction of air flow, a fuel bar directed longitudinally of said passage, and a relatively deep septum crossing the main passage transversely of the Venturi bars adjacent the discharge sides of said bars, said septum carrying intermediate bearings for said throttle bars and providing an intermediate support for said fuel bar.

5. A carburetor comprising a body or casing having a through opening or passage of generally rectangular cross section extending from a face having an enlarged inlet or scoop to an opposite face, the carburetor being provided within said passage adjacent the base of the scoop with a plurality of straight bars in the same plane, said bars being four in number and providing a middle or median Venturi passage and side Venturi passages, the carburetor being provided beyond the discharge of the Venturi passages with a pair of throttle bars turning on axes substantially in line with the respective side Venturi passages and adapted to be moved to a closed position and to various open positions and adapted on first opening to provide a restricted passage at the median portion only of the main passage and on full opening to provide outer passages as well as a median passage, and the carburetor also having in its main passage in a region close to and somewhat beyond said median restricted passage in the direction of air flow, a fuel bar directed longitudinally of said passage, and a septum crossing the main passage transversely of the Venturi bars in the space between the Venturi bars and the throttle bars and provided with an interior chamber and an auxiliary fuel pump in said chamber, said pump discharging forwardly of the throttle bar axes in a location between said axes.

6. A carburetor comprising a body or casing having a through opening or passage of generally rectangular cross section extending from a face having an enlarged inlet or scoop to an opposite face, the carburetor being provided within said passage adjacent the base of the scoop with a plurality of straight bars in the same plane, said bars being four in number and providing a middle or median Venturi passage and side Venturi passages, the carburetor being provided beyond the discharge of the Venturi passages with a pair of throttle bars turning on axes substantially in line with the respective side Venturi passages and adapted to be moved to a closed position and to various open positions and adapted on first opening to provide a restricted passage at the median portion only of the main passage and on full opening to provide outer passages as well as a median passage, and the carburetor also having in its main passage in a region close to and somewhat beyond said median restricted passage in the direction of air flow, a fuel bar directed longitudinally of said passage, and a septum crossing the main passage transversely of the Venturi bars in the space between the Venturi bars and the throttle bars and provided with an interior chamber and an auxiliary fuel pump in said chamber, said pump discharging forwardly of the throttle bar axes in a location between said axes, said septum carrying intermediate bearings for said throttle bars and providing an intermediate support for said fuel bar.

7. A carburetor comprising a body or casing

having a through opening or passage of generally rectangular cross section extending from a face having an enlarged inlet or scoop to an opposite face, the carburetor being provided within said passage with four removable straight bars providing a median Venturi passage and two side Venturi passages, sealing strips interposed between the side faces of the marginal Venturi bars and the adjacent walls of the body, sealing means in connection with the bars disposed along the body walls which are at right angles to said last-named walls, shield plates arranged to provide a flaring scoop portion adjacent the entrance of the main rectangular passage having inner edges leading to the inner edges in proximity to the forward edges of the marginal Venturi bars and having outer edge portions attached to the body walls, the carburetor being provided beyond the discharge of the Venturi passages and within the rectangular main passage with a pair of throttle bars adapted to be turned to a closed position and to various open positions and adapted when in an open position to provide between them a restricted passage, and the carburetor also having in its main passage in a region close to and somewhat beyond said restricted passage in the direction of air flow a fuel bar directed lengthwise of said passage.

8. A carburetor comprising a body or casing having a through opening or passage of generally rectangular cross section extending from a face having an enlarged inlet or scoop to an opposite face, the carburetor being provided within said passage with means providing a plurality of narrow substantially rectangular Venturi passages and being provided beyond the discharge of the Venturi passages with a pair of throttle bars adapted to be turned to a closed position and to various open positions and adapted when in an open position to provide between them a restricted passage, and the carburetor also having in its main passage in a region close to and somewhat beyond said restricted passage in the direction of air flow a fuel bar disposed lengthwise of said restricted passage, the Venturi passage means aforesaid including separate individual straight Venturi bars extending across the passage, plates extending across said Venturi bars at the respective ends and tying them together in a definite spacing, said plates being set in apertures formed in the body at opposite sides of the body, and separate plates attached to the carburetor body exteriorly and cooperating with said first-named plates in holding the Venturi bars firmly in position in a detachable manner, said throttle bars having end bearings supported in said last-named plates.

9. A carburetor comprising a body or casing having a through opening or passage of generally rectangular cross section extending from a face having an enlarged inlet or scoop to an opposite face, the carburetor being provided within said passage with means providing a plurality of narrow substantially rectangular Venturi passages and being provided beyond the discharge of the Venturi passages with a pair of throttle bars adapted to be turned to a closed position and to various open positions and adapted when in an open position to provide between them a restricted passage, and the carburetor also having in its main passage in a region close to and somewhat beyond said restricted passage in the direction of air flow a fuel bar disposed lengthwise of said restricted

passage, the Venturi passage means aforesaid including separate individual straight Venturi bars extending across the passage, plates extending across said Venturi bars at the respective ends and tying them together in a definite spacing, said plates being set in apertures formed in the body at opposite sides of the body, and separate plates attached to the carburetor body exteriorly and cooperating with said first-named plates in holding the Venturi bars firmly in position in a detachable manner, said throttle bars having end bearings supported in said last-named plates and said fuel bar being extended into and supported within one of said last-named plates and being in communication with a fuel supply passage in said plate.

10. A carburetor comprising a body or casing having a main passage through it of generally rectangular cross section, the carburetor being provided within said passage with means providing a plurality of narrow substantially rectangular Venturi passages and being provided beyond the discharge of the Venturi passages with a pair of throttle bars adapted to be turned to a closed position and to various open positions and adapted when in an open position to provide between them a restricted passage, and the carburetor also having in the main passage in a region close to and somewhat beyond said restricted passage in the direction of air flow a fuel bar longitudinally disposed with respect to said passage, the Venturi passage means aforesaid comprising a plurality of straight parallel Venturi bars together with end members tying said bars together in a definite spacing to provide a removable frame disposed in the passage and extended at its ends into apertures at opposite sides of the body, and plate members applied to the body exteriorly in a removable manner and supporting the aforesaid frame in position, said last-named members providing supports for the ends of the throttle bars, one of said members having the fuel bar extended thereinto and the other of said members being provided with a control device having a passage leading to a face of at least one of said Venturi bars.

11. In a carburetor, a casing having a substantially rectangular air-flow passage extending therethrough, Venturi means in said passage in a location spaced from the entrance comprising a plurality of straight bars extending across the passage and defining between them a plurality of rectangular Venturi passages, said Venturi passages comprising a middle passage and two side passages, fuel inlet means comprising a fuel bar arranged in the main passage on the delivery side of said Venturi means and in line with the middle Venturi passage, spaced throttle bars in the main passage between the Venturi means and the fuel inlet means turning on axes in approximate alinement with the side Venturi passages, said throttle bars having edges adapted to meet each other in a line substantially in line with the middle Venturi passage and to be turned to various open positions so as to create a restricted passage substantially in line with the middle Venturi passage, and means in connection with opposite walls of the casing providing masking means for said throttle bars such that on initial opening of said bars air passes them only in the restricted passage between them while on further opening air passes said bars at their outer sides also.

12. In a fuel supply system for an internal

combustion engine, four walls forming an air passage of substantially rectangular cross-section, Venturi means in said passage for producing two unequal pressures whose difference is a measure of the quantity of air flowing thru said passage, said Venturi means comprising a plurality of parallel bars in the same plane, said bars being four in number and providing a central Venturi passage and two side Venturi passages, a pair of substantially rectangular throttle bars in said passage downstream from said Venturi means, said bars turning on axes substantially in line with the respective side Venturi passages and adapted to be moved to a closed position and to various open positions, means for controlling the relationship between angular

throttle movement and the total area of the opening at the throttles including portions of the walls of said passage adjacent the outer edges of said throttle bars formed to contact said outer edges when said throttle bars are in a range of positions adjacent their closed position, so that on first opening of said throttles a restricted passage is provided at the central portion only of said main passage and on further opening outer passages are provided in addition to said central passage, means for supplying fuel to said engine, and means responsive to said difference of air pressures for controlling said fuel supplying means.
